UNITED STATES PATENT OFFICE.

CLAUDE REES, OF SAN FRANCISCO, CALIFORNIA, ASSIGNOR TO REES BLOW PIPE MANUFACTURING COMPANY, OF SAN FRANCISCO, CALIFORNIA.

CHARGER.

Application filed December 24, 1923. Serial No. 682,490.

To all whom it may concern:

Be it known that I, CLAUDE REES, a citizen of the United States, and a resident of the city and county of San Francisco, State of California, have invented a certain new and useful Charger, of which the following is a specification.

The invention relates to a charger for introducing material into a conduit through which a stream of fluid under pressure is passing. Chargers may be used for many purposes and they are used to a large extent for introducing wood shavings, chips and sawdust into a conduit through which a stream of air under pressure is passing, for the purpose of conveying the shavings and sawdust to a remote point. Since the materials which are introduced into the charger are light and since the air passing through the conduit is under pressure, means must be provided for permitting the introduction of the material into the conduit, without any material leakage of air which would tend to blow the light material. This has been accomplished in the past by introducing the material into a closed-bottom container, closing the top of the container, then moving the container so that its bottom is in communication with the conduit and opening the bottom of the container. If there were no pressure in the conduit the material would readily discharge by gravity from the container into the conduit, but, since the air in the conduit is under pressure this air frequently passes into the container with such force as to pack the material therein and prevent it from falling by gravity into the conduit.

An object of the present invention is to provide means for equalizing the pressure in the receptacle on both sides of the charge of material therein, so that the material will readily fall by gravity into the conduit.

Another object of the invention is to provide means for introducing air under pressure into the upper side of the container before the lower side thereof registers with the conduit so that the material is freely discharged from the receptacle into the conduit.

Another object of the invention is to provide means for introducing air under pressure into the upper side of the receptacle during the time that the receptacle is in communication with the conduit, for the pur-

pose of blowing the material from the container into the conduit.

A further object of the invention is to provide an apparatus for introducing successive, complete charges of material into a conduit through which fluid under pressure is passing.

The invention possesses other advantageous features, some of which, with the foregoing, will be set forth at length in the following description, where I shall outline in full, that form of my invention which I have selected for illustration in the drawings accompanying and forming part of the present specifications. In said drawings I have shown one form of apparatus embodying my invention, but it is to be understood that I do not limit myself to such form, since the invention, as set forth in the claims, may be embodied in a plurality of forms.

Referring to said drawings:

Figure 1 is an end elevation of an air blowing apparatus, showing the device of my invention in its environment.

Figure 2 is a cross section of the charger of my invention taken on the line 2—2, Figure 3.

Figure 3 is a cross section of the device taken on the line 3—3, Figure 2.

The device of my invention is used for introducing material into a conduit through which fluid under pressure is passing. The fluid is usually air which is used to convey the material through the conduit to a remote point. When the conduit is of great length a high-pressure blower must be employed for forcing the air through the conduit and these blowers are of such construction that it is not possible to feed the material through the blower, and consequently the material must be entered into the conduit through which the air under pressure is passing. The air is delivered by the high pressure blower 2 into the receiver 3 in which the impulses are smoothed out and the air passes from the receiver through the conduit 4. The conduit 4 is provided with a T 5 which has an upwardly directed opening 6 and the charger of my invention is mounted over this opening.

The charger usually comprises a casing 7 which is preferably cylindrical in form and which is closed at the sides by the plates 8. Journalled in the plates 8 is a shaft 9 to

which is secured a pocket wheel 12. The shaft is rotated by any suitable means such as the electric motor 13 which is connected to the shaft through a suitable gearing 14. 5 The casing 7 is provided on its upper side with an inlet opening 15 which is in communication with the discharge spout 16 of a superposed hopper, in which the material to be introduced into the conduit is accumulated. This material usually consists of wood shavings, sawdust and chips, although it may consist of any other material which it is desired to introduce into the conduit.

15 The pocket wheel 12 is preferably closed at the sides by the walls 17-18 and is open at its periphery. The pocket wheel is provided with a series of pockets 19 defined by the walls 21 extending from the hub to the periphery of the wheel. The material is 20 introduced into these pockets through the inlet opening 15 and, by the rotation of the wheel, the charged pocket is moved to a position over the discharge outlet 22 of the casing and the material is discharged into 25 the T 5. Means are provided for introducing air under pressure into the bottom of the pockets immediately before they open to the discharge outlet 22 to facilitate the discharge of the material from the pockets. 30 This means preferably comprises a second series of pockets 23 in the pocket wheel, the two series of pockets being separated by the intermediate wall 24. The pockets 23 are defined by walls 25 extending from the hub 35 of the wheel to its periphery.

The series of pockets 19 are connected together in pairs with the series of pockets 23, one pocket 19 and one pocket 23 forming a pair. The pocket 23 of each pair leads the 40 pocket 19 so that the pocket 23 comes in communication with the outlet opening 22 in advance of the pocket 19. Arranged in the casing 7, in alignment with the intermediate wall 24 is an annular wall 26, and arranged 45 in alignment with this wall 26 and extending downwardly into the T 5 is a baffle wall 27 which serves to direct air from the conduit 4; upwardly into the pocket 23, as these pockets successively register with the discharge outlet 22.

50 The series of pockets 19 are connected together in pairs with the series of pockets 23 by apertures 28 extending through the intermediate wall 24 at the bottoms of the pockets. As the pocket wheel 12 rotates, a pocket 55 23 of one pair moves into communication with the discharge outlet 22 in advance of the other pocket 19 of the pair. Air under pressure is then introduced into the pocket 60 23 and this air passes through the opening 28 into the associated pocket 19, at the bottom of the charge of material therein, loosens this charge of material and places it under a pressure which is equal to or greater 65 than the pressure to which the pocket 19

will be exposed when such pocket reaches the discharge outlet 22. Consequently, as soon as the pocket 19, which carries the material, reaches the discharge outlet 22, the material in the pocket falls by gravity through the 70 discharge outlet into the T 5. The pockets 19 are much wider than the pockets 23 and, while the pockets 23 may receive some material at the inlet opening 15, this material is blown through the opening 28 into the 75 corresponding pocket 19, when the pocket 23 is exposed at the discharge outlet 22, so that all of the material is readily discharged from the pockets as the wheel rotates. By placing the material in the pocket under a pressure 80 substantially equal to the pressure which exists in the conduit, before the pocket comes into communication with the conduit, the liability of the material being packed into the bottom of the pocket by the pressure of air 85 entering the opening of the pocket is eliminated and all of the material is discharged from the pocket during the time that it is in communication with the discharge outlet. 90

I claim:

1. A charger comprising a casing having inlet and discharge openings, a pocket wheel in said casing disposed between said openings, said wheel having two series of pockets spaced apart axially of the wheel, the pockets in one series leading the pockets in the other series, the corresponding pockets in the two series being in communication at their inner ends. 95

2. A charger comprising a casing having inlet and discharge openings, a pocket wheel in said casing disposed between said openings, a wall intermediate the sides of the wheel dividing the wheel into two series of pockets, said wall being provided with apertures adjacent the bottoms of the pockets, connecting the pockets in pairs, the pockets of one series leading the pockets of the other series. 100

3. A charger comprising a casing having inlet and discharge openings, a pocket wheel in said casing and disposed between said openings, said pockets adapted to receive material from the inlet opening and discharge it through the discharge opening 110 and means for introducing fluid under pressure into the bottoms of the pockets before they reach the discharge opening. 115

4. A charger comprising a casing having inlet and discharge openings, a rotatable 120 pocket wheel in said casing, the pockets successively passing the inlet and discharge openings and adapted to receive material from the inlet opening, carry it to and discharge it through the discharge opening 125 and means for introducing fluid under pressure in the successive pockets after they leave the inlet opening and before they reach the discharge opening. 130

5. A charger comprising a casing having

5 inlet and discharge openings, a rotatable wheel in said casing provided with a pocket adapted to receive a charge of material at the inlet opening and carry the charge to and discharge it through the outlet opening and means for introducing fluid under pressure into the pocket before it reaches the discharge opening.

10 6. A charger comprising a casing having inlet and discharge openings, a rotatable wheel in said casing provided with a pocket adapted to receive a charge of material at the inlet opening and carry the charge to and discharge it through the outlet opening and means for introducing fluid under pressure into the pocket after it leaves the inlet opening and before it reaches the discharge opening.

15 7. A charger comprising a casing having inlet and discharge openings, a rotatable wheel in said casing provided with a pocket adapted to receive a charge of material at the inlet opening and carry the charge to and discharge it through the outlet opening and means for introducing fluid under pressure into the pocket behind the charge therein before the pocket reaches the discharge opening.

20 8. A device for introducing material into a conduit through which a stream of fluid under pressure is passing, comprising a casing communicating at its discharge side with the conduit, a rotatable wheel in said casing having a pocket adapted to receive a charge of the material and convey it to the discharge outlet of the casing and means for diverting fluid under pressure from the conduit into the bottom of the pocket before the pocket reaches the discharge outlet.

25 9. A device for introducing material into a conduit through which a stream of fluid under pressure is passing, comprising a casing communicating at its discharge side with the conduit, a rotatable wheel in said casing having a pocket adapted to receive a charge of the material and convey it to the discharge outlet of the casing and a second pocket in the wheel leading said first pocket and adapted to come into communication with the conduit in advance of the first pocket, said second pocket communicating with the bottom of the first pocket.

30 10. A device for introducing material into a conduit through which a stream of fluid under pressure is passing, comprising a casing communicating at its discharge side with the conduit, a rotatable wheel in said casing having a pocket adapted to receive a charge of the material and convey it to the discharge outlet of the casing and a second pocket in the wheel leading said first pocket and adapted to come into communication with the conduit in advance of the first pocket, and a wall separating said pockets provided with an aperture connecting the bottoms of the pockets.

35 11. A device for introducing material into a conduit through which a stream of fluid under pressure is passing, comprising a casing communicating at its discharge side with the conduit, a rotatable wheel in said casing having a pocket adapted to receive a charge of the material and convey it to the discharge outlet of the casing and a second pocket in the wheel leading said first pocket and adapted to come into communication with the conduit in advance of the first pocket, a wall separating said pockets provided with an aperture connecting the bottoms of the pockets and a baffle wall in alignment with said wall and extending into the conduit to divert fluid under pressure into the second pocket.

40 12. A device for introducing material into a conduit through which a stream of fluid under pressure is passing, comprising a casing arranged above the conduit and provided on its lower side with a discharge outlet connected to the conduit, a rotatable wheel in said casing having two circumferentially disposed series of pockets, the pockets of one series being wide and the pockets of the other series being narrow, the pockets of the narrow series leading the pockets of the wide series, a wall separating said series of pockets provided with apertures connecting the pockets together in pairs at their bottoms and a baffle wall in line with said wall and extending into the conduit to deflect fluid under pressure into the narrow pockets as they open into the discharge outlet.

45 In testimony whereof, I have hereunto set my hand.

CLAUDE REES.
